SWINGING SOOT BLOWER

Fred C. Arey, Oak Park, Ill., and De Los E. Hibner, Jr., Du Bois, Pa., assignors to Vulcan Soot Blower Corporation, a corporation of Pennsylvania

Application June 22, 1935, Serial No. 27,934

6 Claims. (Cl. 257—1)

The present invention relates to soot blowers or cleaners in which there is a tubular cleaning element adapted to swing about an axis other than its own long axis, and which is provided with nozzles to deliver jets of cleaning fluid of the general type disclosed in Fred C. Arey's application filed November 1, 1933, Serial No. 696,174. The object of the present invention is to improve, in certain respects, the construction disclosed in the aforesaid Arey application.

In the said Arey application cleaning fluid is supplied by a pipe to which the tubular cleaning element is fixed, so that in order that the cleaning element may have an oscillatory or swinging movement, the supply pipe must also be movable angularly about its long axis. Furthermore the forces to cause these swinging movements are applied directly to the supply pipe which is thus subjected to comparatively powerful torsional stresses. Viewed in one of its aspects, the present invention may be said to have for its object to produce a simple and novel cleaning or blower unit in which the cleaning element, alone, turns, while the supply pipe remains stationary, and in which the turning forces are applied to the cleaning element, whereby only small turning forces are required.

The various features of novelty whereby our invention is characterized will hereinafter be pointed out with particularity in the claims; but, for a full understanding of our invention and of its objects and advantages, reference may be had to the following detailed description taken in connection with the accompanying drawings wherein:

Figure 1 is a view, partly in front elevation, and partly in section, illustrating a fluid heater equipped in accordance with the present invention; Fig. 2 is a section taken approximately on line 2—2 of Fig. 1; Fig. 3 is a section on a line 3—3 of Fig. 2; and Fig. 4 is a section on line 4—4 of Fig. 2, showing only a fragment of the blower unit and a single wall of the heater.

Referring to the drawings, A represents the casing or housing of a heat interchanger containing vertical open-ended tubular flues B through which hot combustion gases are passed and on the inner surfaces of which soot, ashes and other foreign matter collect. It is the purpose of this invention to keep these flues clean. In the particular arrangement shown, the cleaning means is disposed in the chamber C in the upper part of the housing or casing, so as to be able to blow jets of cleaning fluid, usually steam, down through the flues.

The cleaning fluid, to which we shall refer as steam, is supplied to a horizontal pipe 1 extending across the interior of the compartment C parallel with the rows of flues. This pipe is stationary and mounted thereon is a swinging structure including a tubular cleaning or blowing element 2 which is parallel to the pipe 1. This swinging structure comprises two hollow arms 3, 3 mounted on the pipe 1 close to the front and rear walls of the casing or housing, so as to project radially from the said pipe 1 and be rotatable about the same. These arms are connected together by two long tie rods 4 and 5 extending between and fixed to corresponding ends of the arms. The arms 3 lie almost entirely on one side 5 of the axis of the pipe 1, projecting only far enough in the opposite direction to receive the tie rod 4. On the free ends of the main portions of the arms are suitable heads 6 into which the ends of the cleaner element extend and in which they 10 are journaled so as to permit the cleaner element to turn about its long axis relative to the arms. The arms are provided with relatively long sleeve like parts or hubs 7 that surround and are free to turn on the pipe 1. As best shown in Fig. 4, 15 the pipe 1 is preferably provided with short sections 8 composed of metal adapted to form good bearings for hubs or sleeves 7; each of the sections 8 being provided with suitable external packings 9 placed within the ends of the surrounding hub or sleeve. The bore of the hubs or sleeves is enlarged at the middle to provide an annular space or chamber 10 around the pipe within each hub or sleeve; this space or chamber being positioned between the packings which therefore 20 shut off communication between the latter and the surrounding atmosphere. Each of the pipe sections 8 has therein ports 11 registering with the surrounding chamber 10. Consequently, when steam is supplied to the pipe 1, it flows 25 through the ports 11, through the tubular arms 3, and into the tubular cleaner element from which it is discharged through any usual or suitable nozzles 12.

The parts are so proportioned that when the 30 arms 3 hang down the cleaner element is near the ends of the flues so that jets discharged therefrom can effectively enter the flues. As the cleaner element is swung through its prescribed arc, the jets move from one row of flues to the 35 next row until all of them have been cleaned. It is desirable that the directions in which the jets travel be parallel to the long axes of the flues with which the jets are registering at any given time. This result would not be obtained if 40

the cleaner element were fixed to the supporting arms, because in that case the angles of the jets would change with changes in the angular positions of the arms. We have therefore provided means to turn the cleaner element relatively to the supporting arms while swinging it back and forth, thereby holding the jets parallel to the long axes of the flues.

The swinging of the cleaner element and the turning thereof relatively to its supporting arms is accomplished by a single operating means. The immediate operating means is a shaft 13 near and paralleling the steam pipe 1. Fixed to the shaft are two long, rigid arms 14, each near one of the arms 3. The free end of each of the arms 14 extends between and is secured to a pair of ears 15, projecting laterally from the cleaner element; the connection being in the form of a hinge pin 16. The distance between each hinge pin and the axis of the operating shaft is equal to the distance between the axes of the steam pipe and the cleaner element. Also, the distance between the axes of the operating shaft and the steam pipe is equal to the distance between the axes of each hinge pin and the axis of the cleaner element. Therefore the intersection of these four axes with a plane at right angles thereto mark the four corners of a parallelogram whose opposite sides must of course always remain parallel to each other. Thus it follows that when the operating shaft is turned in one direction, the arm 14 pulls the swinging frame along, (the ears on the cleaner element and the element itself serving as connecting links) and causes the cleaner element to turn in the frame and compel the nozzles always to point in the proper direction. When the shaft is turned in the opposite direction, the arms thereon push the swinging frame ahead of them, simply reversing the movements of the parts.

It will be seen that the forces that are applied to the swinging frame to move it, take effect at points remote from the swinging axis, so that their leverage is great and the forces need be only small ones. Furthermore, the steam pipe serves only as a conduit and as a journal on which the swinging frame is mounted, so that the only load upon the same is that due to the weight of the swinging frame and its counter-balances 17.

The operating shaft may be turned by any suitable means. In the arrangement shown, there is a toothed segment 18 fixed on one end of this shaft. Meshing with this segment is a pinion 19 fixed to a short shaft 20. On the outer end of the shaft 20 is a sprocket wheel 21 around which extends a sprocket chain 22. This chain may form part of an endless flexible member extending to any suitable point for manual operation or to be controlled in some other manner.

The supply of steam to the pipe 1 may be controlled in any usual or suitable way. In the arrangement shown, steam is delivered through a line 23 that leads to a valve 24 connected to the front end of the pipe 1. This valve has an actuator 25 in the form of a pulley 25 over which runs a chain 26. By pulling on one end of the chain 26 the valve will be closed whereas, when the other end is pulled, the valve will be opened.

While we have illustrated and described with particularity only a single preferred form of our invention, we do not desire to be limited to the exact structural details thus illustrated and described; but intend to cover all forms and ar-

rangements which come within the definitions of our invention constituting the appended claims.

We claim:

1. In a fluid heater cleaner, a stationary pipe for supplying cleaning fluid, a tubular blower element spaced apart from and paralleling said pipe, means supporting said blower element from said pipe for swinging movements about the axis of the latter and for placing the interior of the blower element in communication with the interior of the pipe, means for swinging said blower element about said pipe, and means for causing relative turning movements between the blower element and the supporting means therefor while the blower element is making swinging movements.

2. In combination, a group of vertical open-ended tubes or flues, a stationary horizontal pipe mounted at some distance from the ends of said tubes or flues, a horizontal tubular blower element located near the open ends of said tubes or flues, means supporting said blower element from said pipe and placing the interior thereof in communication with the interior of the pipe, and means for swinging said blower element about said pipe and simultaneously causing it to turn about its own axis.

3. In a fluid heater cleaner, a supporting member mounted for swinging movements, a tubular blower element mounted on said member with its axis spaced apart from and parallel to the axis about which said member swings, said blower element being adapted to turn relatively to the supporting member about its own axis, a shaft near and parallel to the said axis of the supporting member, an arm fixed to said shaft and extending into the vicinity of said blower element, a link connecting the said arm to the blower element, the said link being as long as the distance between the axis of the shaft and the aforesaid axis of the supporting member and being parallel to a plane containing the two latter axes, and means for turning said shaft.

4. In a fluid heater cleaner, a stationary horizontal pipe, tubular arms projecting radially from said pipe, means connecting said arms to said pipe so as to support them for swinging movements about the axis of the pipe, a tubular blower element extending between and rotatable in the outer ends of said arms, the parts being so constructed and arranged that the arms place the blower element in communication with the interior of the pipe, a shaft near and parallel to said pipe, an arm fixed to said shaft and extending therefrom to a point near the blower element, a link connecting the said arm to the blower element, the effective length of the arm being equal to the distance between the axes of the pipe and the blower element, the effective length of said link being equal to the distance between the axes of the pipe and the shaft, and means to turn the shaft.

5. In a fluid heater cleaner, a supporting member mounted for swinging movements, a tubular blower element mounted on said member with its axis spaced apart from and parallel to the axis about which said member swings, said blower element being adapted to turn relatively to the supporting member about its own axis, means to deliver cleaning fluid into the blower element, a shaft near and parallel to the said axis of the supporting member, a rigid arm fixed to said shaft and extending into the vicinity of said blower element, a link connecting the said arm to the blower element, the said link being as long as

the distance between the axis of the shaft and the aforesaid axis of the supporting member and being parallel to a plane containing the two latter axes, and means for turning said shaft.

5. 6. In a fluid heater cleaner, a stationary horizontal pipe, arms at least one of which is tubular projecting radially with respect to said pipe, means supporting said arms for swinging movements about the axis of said pipe, a tubular blower element extending between and rotatable in the outer ends of said arms, the parts being so constructed and arranged that the arms place the blower element in communication with the

interior of the pipe, a shaft near and parallel to said pipe, a rigid arm fixed to said shaft and extending therefrom to a point near the blower element, a link connecting the said arm to the blower element, the effective length of the arm being equal to the distance between the axes of the pipe and the blower element and, the effective length of said link being equal to the distance between the axes of the pipe and the shaft, and means to turn the shaft.
